(57) **CLAIM**

The ornamental design for a tape cutter and holder, as shown and described.

DESCRIPTION

FIG. 1 is a perspective view of a tape cutter and holder showing my new design in environmental use;
FIG. 2 is a perspective view thereof;
FIG. 3 is a rear elevational view thereof;
FIG. 4 is a left side elevational view thereof;
FIG. 5 is a top plan view thereof;
FIG. 6 is a right side elevational view;
FIG. 7 is a front elevational view thereof; and,
FIG. 8 is a bottom plan view thereof.
The broken lines showing environment in the drawings are included for illustrative purposes only and form no part of the claimed design.
